LIQUID FUEL BURNER

Perry R. Johnson, Chicago, Ill.

Application August 18, 1932, Serial No. 629,337

6 Claims. (Cl. 158—89)

This invention relates to improvements in a liquid fuel burner of the type primarily used for heating stoves and ranges.

My improvements are directed to the design of a liquid fuel burner in which the fuel is vaporized and burned in an annular chamber to which air is admitted through perforated walls surrounding the combustion space.

It is an object of my invention to disclose a design of fuel burner which is highly efficient and economical in the consumption of fuel and in which the combustion of the fuel vapor will take place substantially throughout the height of the burner, whereby an intense heat is developed.

15 A particular object of my invention relates to the design of the cylindrical screens which form the dividing walls between the combustion space and the air. I have found that by punching out small strips of material substantially over the entire area of the dividing wall in such a manner that the strips are integral at their ends with the wall and separate from the body metal on the upper and lower sides thereof, that there will be formed a dividing wall having a plurality of openings through which air may flow and be baffled and spread to flow both upwards and downwards into the combustion space. An important function of my improved dividing wall is to prevent direct lateral admission of the air 20 into the combustion space and to avoid entrance of the air all in the same direction, such as upward, but instead the air is caused to flow into the combustion space both upwards and downwards at a plurality of points.

30 Further improvements of my invention are directed to the novel design of means within the center portion of the burner intended to draw the heat down from the top portion of the burner and to spread the heat throughout the lower portion of the burner in such a manner as to preheat the fuel and air.

Various other features of novelty and advantages of my improvements will be more readily apparent from the following description taken in 45 connection with the attached drawings.

Figure 1 is an elevation of a burner unit;
Figure 2 is a sectional elevation taken on the plane indicated 2—2 in Figure 3;
Figure 3 is a plan view of the burner unit;
50 Figure 4 is a plan view of the base;
Figure 5 is a partial horizontal section taken through the reticulated screens and shown at an enlarged scale;
Figure 6 is a partial horizontal section similar 55 to Figure 5 but illustrating a modification.

The burner is designed for installation in a stove, range or other heating device to be used for cooking or heating purposes. The liquid fuel may be fed from a suitable reservoir in such a manner as to maintain a constant lever fuel within the burner. The liquid fuel is conducted to the burner through the pipe 10 which is connected to the base member 12.

As shown in the plan view of the base 12 in Figure 4, the fuel is directed upwardly through the pipe 10 through a passage 14 into an annular trough 16. The base has a central circular opening 18 surrounded by a cylindrical wall 20. The wall 20, as shown in Figure 2, extends for some distance above the bottom of the trough 16. The trough 16 is substantially surrounded by a raised rib 22 which is spaced outwardly with respect to the cylindrical wall 20. However, the rib has a cut-away portion 24 which permits flow of the fuel into a second trough 26, the bottom of which is somewhat below the bottom of the first trough 16. The trough 26 is surrounded on its outer side by the raised cylindrical rib 28 which extends substantially to the same level as the inner cylindrical wall 20. Finally the base member 12 has integrally formed therewith an outer ring-shaped member 30 which is supported from the inner ring-shaped portion by spaced bosses 32, thereby leaving openings 34 which, as will be later apparent, permit the upward flow of air.

The outer ring 30 forms an annular fuel feeding groove 36 surrounded by an inner raised rib 38 and an outer raised rib 40. The bosses 32 include passageways 42 which as illustrated in Figure 2, permit flow of the fuel from the trough 26 into the outer annular groove 36. The groove 36 is adapted to receive an annular wick 44, the top of which may be trimmed to extend slightly above the ribs 38 and 40. The ribs 38 and 40 are rabbed in order to serve as supports for cylindrical reticulated screen members.

Thus, there is provided an outer screen member 46 supported and positioned by the cylindrical rib 40. A smaller screen 48 is mounted inside of the rib 38. A still smaller cylindrical screen 50 is positioned by the cylindrical rib 28. The innermost screen 52 is supported on a removable block 54 which has a cylindrical portion 56 fitting within the central opening 18 of the base member 12. The member 54 has an enlarged ring-shaped portion 58 which seats upon the circular rib 20 and substantially covers the innermost oil feeding trough 16. The ring-shaped portion 58 is upwardly flanged in order to position the cylin- 110

drical screen 52 which seats within the flanged edge.

It will be apparent that the four cylindrical screens are concentrically mounted. The screens 5 46 and 48 define an annular combustion space 60. The screens 50 and 52 define an annular combustion space 62. The annular space 64 between the screens 48 and 50 receives air from the openings 34 in the base member in order to feed the 10 air into the combustion spaces.

The top of the burner illustrated in Figures 1 and 2 includes a removable cap member 66. The central portion of the cap member 66 is of substantially the same diameter as the inner screen 15 52 in order to close the open upper end thereof. The cap member 66 also includes a ring-shaped portion 68 adapted to cover the annular space 64 between the screens 48 and 50. The ring-shaped portion 68 is supported from the inner portion 20 of the cover member by spaced radial arms 70. The arms 70 have integral lug portions 72 depending into the combustion space 62 and serving to hold the screens 50 and 52 in proper position. The arms 70 also include depending lugs 74 fitting into the combustion space 60 and serving to 25 position the screens 46 and 48.

The particular formation of the reticulated cylindrical screens is a novel feature of the present improvements. The new design is most clearly illustrated in the enlarged view of Figure 5. It will be noted that annular strips of the continuous cylindrical wall are pressed into the shape shown by sectional view of Figure 5. Thus, the outer screen 48 includes strips 76 which present 30 a wavy or corrugated appearance, portions of the strips being pressed inwards to such an extent as to leave vertical openings 78, as viewed from the upper end of the cylindrical screen. It will therefore be understood that air may pass into 35 the combustion space either upwards or downwards through the vertical opening 78 but the air is prevented from passing directly inwards due to the shielding effect of the continuous material in the screen 46. On the other hand the 40 flames cannot pass directly outwards as would be possible if the material was punched out to leave free openings. It will be noted that the corrugations are pressed inward from the exterior of the cylindrical member 46 while in the cylindrical member 48 the corrugations are pressed outwardly. Thus the burning of the combustible vapor 45 in the annular space 60 produces a suction action tending to draw in air from both sides of the combustion space. This action occurs throughout 50 the entire height of the cylindrical screens.

A modified design is shown in Figure 6 in which the corrugations 80 and 82 are pressed outwardly with respect to the combustion space. It is believed that the form shown in Figure 5 is more desirable since the inward pressed corrugations 55 tend to promote agitation and mixing of the combustible vapor.

It is highly desirable in order to obtain complete combustion of the fuel vapor to insure burning of the vapor entirely throughout the height 60 of the burner and I have shown in Figure 2 an element which is of assistance in conducting the heat downwardly from the top portion of the burner which is normally the hottest portion of the burner and to throw out the heat adjacent the bottom of the burner. This element also serves to some extent in preheating the incoming air and fuel. I show a cone-shaped member 75 84 which is seated upon the part 54. This cone-shaped member is composed of a lava prod-

uct which is refractory and which becomes incandescent when highly heated. Thus as the top of the cone becomes heated, the heat is conducted downwardly and spread outwardly until the entire cone is incandescent, whereupon the heat at the bottom of the cone is taken up by the fuel vapor rising through the annular combustion space 62.

According to my invention, a more efficient combustion of the fuel is obtained throughout the entire vertical height of the burner. It is found particularly important to trap the flame combustion within the combustion space and, by the manner in which I have formed the baffled air admission apertures in the shells, the flame does not travel rapidly upwards to concentrate the heat at the top of the burner but instead the air is drawn inwards to pass both upwardly and downwardly within the combustion space and to prevent rapid movement of the flame. Furthermore, by the use of the refractory elements, which become incandescent when highly heated, the heat is retained in the burner and the bottom of the portion of the burner is maintained substantially as hot as the top portion. It has been found that a much higher temperature can be obtained when the refractory elements are employed than without such elements.

I claim:

1. In an oil burner, spaced, concentric walls forming an annular combustion chamber therebetween, one of said walls including a plurality of openings therethrough, said openings being formed by strips of the wall material pressed from the body of said wall inwardly into said chamber in such a manner as to form vertically open passages beneath and above each strip adjacent to the surface of said wall.

2. In an oil burner, a pair of cylindrical metallic members concentrically positioned and spaced to form an annular combustion chamber therebetween, said metallic members having apertures to admit air to said combustion chamber, the apertures in said metallic members being shielded by strips of metal pressed inwardly into said chamber from the body of said metallic members in such a manner as to form vertically open passages beneath and above the strips and in communication with the apertures of said members.

3. In an oil burner a pair of cylindrical metallic members forming inner and outer walls of an annular combustion space, each of said metallic members having a plurality of air admission apertures formed by inwardly pressed strips of metal, each of said strips being cut away from the body of the metallic members in such a manner as to form vertically open passages within the combustion space beneath and above each strip of material for conducting the admitted air upwardly and downwardly into said combustion space for mixing with the combustible vapor.

4. In an oil burner having an annular combustion space formed by an apertured wall, said wall having strips of the wall material pressed from the body of the wall to form the apertures thereof, said strips serving as baffles for directing the air drawn into the combustion space upwardly and downwardly therein.

5. In an oil burner, a pair of cylindrical shells forming an annular combustion space therebetween, each of said shells having a plurality of air admission apertures and baffles within the

- combustion space adjacent each of said apertures for directing the incoming air upwardly and downwardly within said combustion space.
6. In a liquid fuel burner, a fuel receiving trough, a pair of inner and outer cylindrical shells supported upon said trough and forming an upwardly extending annular combustion space, said shells having a plurality of air admission apertures throughout the height thereof, means 10 for baffling the air drawn into said combustion space through said apertures to cause said air to flow both upwardly and downwardly from each aperture into said combustion space and a heat-absorbing refractory member within the inner of said shells, said member having an increasing cross sectional area from the top towards the bottom thereof, said member being adapted to become incandescent throughout when the burner is in operation. 80
